(57) **CLAIM**

The ornamental design for a canister spout, as shown and described.

DESCRIPTION

FIG. 1 is an exploded perspective view of a canister spout according to the invention;

FIG. 2 is a side view of the canister spout;

FIG. 3 is a front view of the canister spout;

FIG. 4 is a rear view of the canister spout;

FIG. 5 is a top view of the canister spout; and,

FIG. 6 is a perspective view of a canister spout.

The broken line showing of structure is for illustrative purposes only and forms no part of the claimed design.
